UNITED STATES PATENT OFFICE.

THOMAS T. RISSINGER, OF COMPTON, CALIFORNIA.

CURLING INSTRUMENT.

Application filed July 31, 1926. Serial No. 126,232.

My invention relates to improvements in apparatus for curling hair.

The principal object of my invention is to provide simplified and improved apparatus for curling eye lashes.

Another object of my invention is to provide heat transmitting apparatus wherein heat is transmitted partly by radiation.

Another object of my invention is to provide an adjustable hair curling instrument.

Referring to the drawings in which the same numbers indicate like parts:—

Fig. 1 is a side elevation, partly in section, of my apparatus.

Fig. 2 is a front view of Fig. 1.

Fig. 3 is a part view looking down on Fig. 1.

Fig. 4 is a top view of a detail.

Fig. 5 is a side view of part of Fig. 3 in an operative position.

Fig. 6 is a view of part of the construction of Fig. 1.

My invention includes generally an apparatus resembling a pair of pliers comprising an upper arm 1 and a lower arm 2 suitably pivoted at 3, and such may be suitably held apart by a light spring 4.

Said arms may be of channel construction whereby wires 5 and 6 may pass through arm 1 to convey suitable current through a proper resistance 7 for a heating element, the current flowing upon closing switch 8.

Arm 1 terminates in an upper compression bar 9 adapted to fit in a lower compression socket 10 mounted on the end of an arm 2^a, pivoted to arm 2 at 11, and arm 2 is normally held in a predetermined relation with arm 2^a by a spring 12. Bar 9 is made of solid metal of predetermined circular cross-sectional area, the radius of which is slightly less than the radius of socket 10 which is of arcuate form.

An abutment 13 is provided on arm 2 to receive an adjusting member 14 threaded for movement therein and being held in predetermined position thereto by a lock-nut 15.

The extremity of arm 1, to which bar 9 is attached, may be hollow to receive wires 5 and 6 which are suitably insulated until they pass through arm 1 and join the resistance 7, resistance 7 being suitably insulated from arm 1 by an insulating pad 16, shown in Fig. 6 is being composed of asbestos etc. having a plurality of holes 17 punched therein. The outer covering for resistance 7 in-

cludes suitable solid heat and electrical insulation 18.

In the art of hair curling it is customary to apply heat in various forms to the hair whereby a more or less permanent deflection of the same is imparted. Where the hair is short this is a very difficult operation to be done individually and in order to impart the proper deflection I am now enabled to do this expeditiously and at the proper degree of heat through individual effort.

The operation is as follows:—

Upon closing switch 8, wires 5 and 6 being connected to a suitable source of current, the current flows through resistance 7 thereby heating the same and the heat is transmitted partly by radiation through holes 17 to arm 1 and thence by conduction to the bar 9. Of course, depending on the insulation 16, part of the heat from resistance 7 is also transmitted by conduction through insulation 16 itself.

After a predetermined application of current to resistance 7, bar 9 reaches a certain temperature and this temperature I have found should not be greater than 140° Fahrenheit for my specific object of curling eye lashes.

At the right time after the proper heat has been transmitted to bar 9, the apparatus as a whole is placed against the cheek in proper determined relation depending on adjustment 14, whereby the upper eye lash 19 may rest on socket 10 substantially as shown in Fig. 1. Arms 1 and 2 are then compressed whereby bar 9 is brought over eye lash 19 thereby forcing eye lash 19 into substantially parallel relation with socket 10. However, in order to give the proper upward curl to the upper eye lash 19 it is necessary to have the vertical axis of socket 10 substantially at right angles to the juncture line of eyelids 20 when the same are closed.

In this manner bar 9 is arranged when closing to just miss the upper edge 21 of socket 10 and to be restrained from further downward movement by the lower edge 22 of socket 10. As soon as bar 9 is restrained by lower edge 22, a further compression of arms 2 and 1 causes a forward longitudinal movement of socket 10 and arm 2^a due to a straightening effect thereof permitted by the pivot 11 whereby the eye lash 19 is forced into complete parallel contact with socket 10 as shown in Fig. 5. This contact may be

maintained for a predetermined period of time and upon release of the compression exerted by arms 1 and 2, eye lash 19 will be found to have assumed the proper upward curling deflection.

It will be seen therefore that normally, when arms 1 and 2 are apart, the radial distance from pivot 3 to bar 9 will be slightly greater than the radial distance from pivot 3 to the upper edge 21 of socket 10. When bar 9 is compressed into socket 10 this radial distance will decrease due to the straightening effect of arm 2 against the tension of spring 12.

As already stated, a maximum degree of heat only is desired because the eyelids are very sensitive portions of the human body and it is desirable that bar 9 should not touch the same otherwise the operation may be made difficult of performance. As an aid to curling, the eye lash 19 may be moistened with water prior to the application of heat, but while such is desirable it is by no means necessary.

It should be noted that, as shown in Figs. 3 and 4, socket 10 and bar 9 are of arcuate form longitudinally in order that they should fit the natural curve of an eyelid thereby curling all of the eye lashes thereon in one application of heat.

It is understood of course, that many modifications can be made, for instance, it is obvious that bar 9 may be suitably insulated from arm 1 and itself comprise, or include the resistance 7. Also the heating effects may be reversed by applying the resistance windings to arm 2 thus heating socket 10.

I claim:—

1. Apparatus for curling hair including a compression bar, and a compression socket, pivoted together, the radial distance of each from the pivot point being different, and means to cause said radial distances to approach equality.

2. Apparatus for curling hair including a heated compression bar, and a compression socket, pivoted together, the radial distance of each from the pivot point being different, and means to cause said radial distances to approach equality.

3. Apparatus for curling hair including a compression bar, and a compression socket of arcuate form, pivoted together, the radial distance of each from the pivot point being different, and means to cause said radial distances to approach equality.

4. Apparatus for curling hair comprising a socket having longitudinal and vertical cross-sections of arcuate form and a compression bar adapted to fit in said socket upon longitudinal movement of the socket.

5. Apparatus for curling hair comprising a socket having longitudinal and vertical cross-sections of arcuate form, a compression bar adapted to fit in said socket upon longitudinal movement of the socket, and means to heat hair held between said bar and socket.

6. Apparatus for curling hair comprising a socket having longitudinal and vertical cross-sections of arcuate form, a compression bar adapted to fit in said socket upon longitudinal movement of the socket, and means to heat by radiation hair held between said bar and socket.

7. Apparatus for curling hair comprising a socket having longitudinal and vertical cross-sections of arcuate form, a compression bar adapted to fit in said socket upon longitudinal movement of the socket, and electrical means to heat hair held between said bar and socket.

8. Apparatus for curling hair comprising a socket having longitudinal and vertical cross-sections of arcuate form, a compression bar adapted to fit in said socket upon longitudinal movement of the socket, and means to heat said bar not to exceed 140 degrees Fahrenheit.

9. Apparatus for curling hair comprising a compression bar, a compression socket, means to compress a hair in substantial parallelism with the bar and socket and means to maintain the bar, socket, and hair in relatively fixed position with respect to the cuticle to which the hair is attached.

Signed at Los Angeles, in the county of Los Angeles and State of California, this 21 day of July A. D. 1926.

THOMAS T. RISSINGER.
